UNITED STATES PATENT OFFICE.

DELCIE D. BEAN, OF EAST JAFFREY, NEW HAMPSHIRE.

REINFORCED BOX.

Application filed July 1, 1921. Serial No. 481,936.

To all whom it may concern:

Be it known that I, DELCIE D. BEAN, a citizen of the United States, residing at East Jaffrey, in the county of Cheshire and State of New Hampshire, have invented certain new and useful Improvements in Reinforced Boxes, of which the following is a specification.

The object of this invention is to provide a new and improved form of box construction. Another object of the invention is to provide reinforcement for the box so constructed.

These and other objects of the invention will be fully illustrated in the drawing, described in the specification and pointed out in the claims at the end thereof.

In the accompanying drawing:

Figure 1 is a perspective view of the corner of one of my improved boxes showing the interlocking joint and the method of nailing.

Figure 2 shows one of my improved boxes with a panel end corresponding to style No. 2 as recognized and adopted by the National Association of Box Manufacturers.

Figure 3 is a perspective view of one of my improved boxes with a panel end having mitered joints corresponding to style No. 3 as recognized and adopted by the National Association of Box Manufacturers.

Figure 4 is a perspective view of one of my improved boxes with cleats on the ends thereof corresponding to style No. 4 as recognized and adopted by the National Association of Box Manufacturers.

In the drawings, like reference numerals indicate like parts.

In the drawings, reference numeral 1 indicates one side of the box and reference numeral 2 indicates the other side of the box. Reference numeral 3 indicates one end of the box and reference numeral 4 indicates the other end of the box. As shown the sides 1 and 2 are each made of more than one piece of lumber and the ends 3 and 4 are each made of more than one piece of lumber, and while this is the preferred construction of a box of a particular dimension, it will be understood that the sides and ends of a box of the same dimension could each be made of a single piece of lumber or could be made with any number of pieces in each of the ends or sides so long as the interlocking joints could be formed therein and so long as the sides and ends could break joints

with each other. It will also be understood that all of the tongues will preferably be of the same width and the recesses will be of the same width to correspond, although the tongues on the sides could be of one width and the tongues on the ends of a different width, the recesses that receive them being made of a width to correspond.

As shown in Figure 2 the side 5 is composed of two boards 6 and 7, the board 6 having a long recess therein. The end is formed of the boards 8 and 9 which together have a tongue formed on the end thereof adapted to fit the recess in the end of the board 6. The joint between the boards 8 and 9 occurs well out of line with the joint in the boards 6 and 7. The tongues of the boards 6 and 7 are nailed directly to the boards 8 and 9 by nails 10, 10, that pass transversely thru the tongues and longitudinally into the boards 8 and 9 and the tongue on the boards 8 and 9 is nailed to the board 6 by nails 11, 11, that pass transversely thru the tongue and longitudinally into the board 6.

It will also be understood that the recesses in each board are cut equal in depth to the width of the board and a tongue is left on either side of the recess or between the recesses projecting a distance equal to the thickness of the board. The tongues on the side engage with and fill the recesses on the ends and the tongue on the ends engages with and fills the recess on the side and as the tongues and recesses are large and few in number the parts interlock very advantageously, and they are held together by nails driven thru the tongue, the nails driven thru one set of tongues standing at right angles to the nails driven thru the other set of tongues, the nails thus forming a brace which holds the box in shape with great rigidity.

In Figure 2 I have shown a box made in this manner reinforced on the end by a panel of a well known type. The panel is fastened to the box by long nails which pass thru the uprights of the panel and thru the tongues on the ends and into the boards of the sides. These nails passing thru the three parts serve to further interlock the parts and firmly hold them together. Other long nails pass through the tongues directly into the sides. Elsewhere the panel is fastened to the ends with small nails which are clinched on the inside of the box.

In Figure 3 I have shown a box with a

panel having mitered joints corresponding to style 3 recognized and adapted by the National Association of Box Manufacturers. The uprights of this panel are fastened to the ends and side of the box in the same manner as above described in style No. 2. The box itself is made with interlocking joints substantially the same as shown in Figures 1 and 2.

- 10 In Figure 4 I have shown a box made with the same kind of interlocking joints, the ends of the box being reenforced by cleats 20 and 21 which project above and below the body of the box and overlap the top and bottom of the box. These cleats tie the top and bottom to the box in the well known manner.

It will be understood that the tongues and recesses in which they rest or fit, go together very easily and are not intended to be held together by friction but preferably make a loose fit, rather than a tight or driven fit, and boxes of this type are being made in both large and small sizes and are not to be confused with the so-called lock corner boxes in which the sides are driven together with great force and depend on friction and glue to hold them together, which boxes are only made in comparatively small sizes.

- 20 Applicant's boxes for holding several hundred pounds each are made of 5/8" lumber, where ordinarily 7/8" lumber would be required, and these boxes have stood as well and even better than the boxes made in the old way of 7/8" lumber. Boxes made of 5/8" lumber holding about three hundred pounds each are being regularly used for shipping cloth in sizes about 42" x 38" x 30" with satisfactory results
- 35 40 and can be used for the shipment of all bulky and heavy commodities with a great saving in lumber and weight.

I claim:

1. A box, having sides and ends, each having wide tongues with recesses between

them, the tongues on each member making interlocking engagement with the recesses in the adjacent member, each tongue being fastened to the adjacent member at the corner by one or more nails driven transversely thru the tongue and longitudinally into the adjacent member, the nails at each corner extending thru one set of tongues transversely to the nails extending thru the other set of tongues, cleats on the ends of the box overlapping the end and the exposed tongues and having nails driven thru the cleats and tongues and into the sides.

2. A box having sides and ends, each side and end being made up of a plurality of parallel boards laid side by side of a single thickness rectangular, large tongues and recesses formed in the ends of said sides and ends, the tongues of the ends extending into the recesses of the sides and overlapping the joints between the boards of the sides, and the tongues of the sides extending into the recesses of the ends and overlapping the joints of the boards of the ends, nails driven into the outside of the tongues of the sides and ends to alternately lock the tongues into the recesses at right angles to each other and lock the parallel boards of the sides and ends on top of each other, the boards on each side or end being held together by the nails driven through the tongues on an adjacent end or side, each tongue being fastened to the adjacent member at the corner by one or more nails driven transversely thru the tongue and longitudinally into the adjacent member, the nails at each corner extending thru one set of tongues transversely to the nails extending thru the other set of tongues, cleats on the ends of the box overlapping the end and the exposed tongues and having nails driven thru the cleats and tongues and into the sides.

In testimony whereof I affix my signature.

DELCIE D. BEAN.
